UNITED STATES PATENT OFFICE.

PAUL DRUSEIDT, OF REMSCHEID, GERMANY.

ELECTRIC SWITCH OR CUT-OUT.

1,052,903.

Specification of Letters Patent. Patented Feb. 11, 1913.

Application filed April 28, 1910. Serial No. 558,175.

To all whom it may concern:

Be it known that I, PAUL DRUSEIDT, a subject of the Emperor of Germany, residing at Remscheid, Germany, have invented certain new and useful Improvements in Electric Switches or Cut-Outs, of which the following is a specification.

My invention relates more particularly to improvements in electric cut-outs of that kind in which loose switch members, preferably balls, are employed. Some of these switch members have a conductive surface and the other have an insulating surface. When a switch member having a conductive surface is moved in engagement with a portion of the device where the electric circuit is interrupted, the closing of the circuit will be effected. When, however, a switch member having an insulating surface is moved to that portion or between two open ends of a circuit, the circuit will remain open.

A constructional form of a switch according to this invention is shown by way of example in the accompanying drawing, in which:

Figure 1 illustrates a cut-out in elevation and partly in section. Fig. 2 is a partial section on the line A—B of Fig. 1; and Fig. 3 is a section on the line C—D of Fig. 1.

Referring particularly to the drawings *a* represents a switch casing, which is provided with a cavity or chamber *b* defined by cylindrical or helicoidal walls. Extending into the lower portion of this chamber is a push pin *h* which projects through the front portion of the casing. A suitable spring *s*, is provided, which normally acts to force the button outwardly. Contact members *e*, *e'*, insulated from one another enter the cavity *b* and are approximately parallel to each other. The contact members are resilient with respect to each other and may be curved at their ends. They are secured in some suitable manner in the casing *a* and are electrically connected with the conductors *f*, *f'*, respectively. The contact members are preferably made of bronze. Two balls *c*, *d*, are loosely arranged within the cavity *b*, the ball *c* being made of a conductive material, for instance metal and the ball *d* being formed of non-conductive material. When the ball *c* made of conductive material is engaged between the ends of the contact members, *e*, *e'*, the circuit is closed, as cur-

rent may flow from the conductor *f* to the contact member *e*, thence through the ball *c* to the contact member *e'*, and finally to the conductor *f'*. The other ball constructed of insulating material rests then, as may be seen upon reference to Fig. 1, in front of the push pin *h*. When the said push pin is moved inwardly, it presses the ball *d* against ball *c*, and as the movement is continued, it presses the last-named ball *c* out of its position of engagement between the contact members *e* and *e'*, substituting therefor the ball *d* in the same position. As this ball *d* is made of insulating material, the circuit will be interrupted. The ball *c* formerly between the contact members *e* and *e'*, rests now on top of the push pin *h*. When the push pin is retracted, the ball drops in front of the push pin, as is shown in Fig. 1 with respect to ball *d*, so that after pressing on the pin again the same operation is repeated, only with the difference that now the insulating ball will be removed from engagement between the contact members *e* and *e'* and will be substituted by the conductive ball. The circuit previously interrupted is then again closed. It is important in order to insure the operation just described, that the inner wall of the casing, that is, the wall of the chamber or cavity *b*, be curved, the said wall being engaged by the balls actuated by the push pin. The ball between the contact springs does not move in the same direction as the push button. The ball which has been in engagement between the contact pins therefore travels in a path different from that of the pressure member, and it travels upwardly so that in spite of the horizontal movement of the push pin, the switching ball rises and after having left the elevated position between the contact springs *e*, *e'*, it rolls back again in front of the push pin so that the operation may be repeated. For the purpose of insuring the operation as described, a portion of the inner wall of the casing, *b*, is curved in an approximately semi-circular shape above that which is in engagement with the ends of the contact springs *e* and *e'*, so as to guide the expelled ball in the desired direction of travel.

For the purpose of securely holding the balls between the contact members *e* and *e'*, the free ends of the latter are provided each with a spherical concavity *m*, the shape of which may be clearly seen upon reference

to Fig. 3. It will also be advisable to make the contact members resilient for the purpose of effecting a rapid engagement and disengagement of the balls and furthermore for obtaining complete contact.

The arrangement of two contact springs in opposition has the advantage that the balls adjust themselves automatically with respect to the axis of the push button.

- 10 There are therefore no lateral forces acting upon said push button so that the same is more readily movable and is not subjected to excessive wear. It will be sufficient, however, to make only one of the contact members 15 resilient and at the same time obtain the above-mentioned advantage with respect to wear on the push button.

I claim:—

1. In an electric switch, the combination 20 of a casing provided with an interior chamber, a pair of switch members loosely arranged within said chamber, one of which has an electrically conductive surface while the other has a non-conductive surface, a 25 pair of contact members arranged within said chamber, said contact members being suitably spaced apart, a push pin mounted in said casing and entering said chamber for moving one of said switch members 30 into engagement between said contact members, said push pin being movable in an approximately horizontal direction, a wire terminal electrically connected with each contact member, one switch member being 35 normally in engagement between said contact members, and another switch member being normally in a position between said contact members and said push pin, the engaging ends of said contact members being 40 disposed close against the wall of said chamber and a portion of said wall which extends above said contact members being inclined forwardly with respect to the axis of movement of the push pin, whereby the 45 switch member which is expelled from engagement between said contact members is prevented from traveling in the same direction as the push pin moves and is guided upwardly and forwardly from said contact members so as to drop in front of the push pin.

2. In an electric switch, the combination 55 of a casing provided with an interior chamber, a pair of balls loosely arranged within said chamber, one of which has an electrically conductive surface while the other has a non-conductive surface, a pair of contact arms arranged within said chamber, said contact arms being suitably spaced apart, 60 a push pin mounted in said casing and entering said chamber for moving one of said

loose balls into engagement between said contact arms, said push pin being movable in an approximately horizontal direction, one ball being normally in a position between said contact arms and said push pin, the ball-engaging ends of said contact arms being disposed against the wall of said chamber and a portion of said wall which extends above said contact arms being curved and inclined forwardly with respect to the axis of movement of the push pin, whereby the loose ball which is expelled from engagement between said contact arms is prevented from traveling in the same direction as the push pin moves and is guided upwardly and forwardly from said contact arms so as to drop in front of the push pin, and a wire terminal electrically connected with each contact arm.

3. In an electric switch, the combination 80 of a casing provided with an interior chamber, a pair of balls loosely arranged within said chamber, one of which has an electrically conductive surface while the other has a non-conductive surface, a pair of resilient contact arms suitably spaced apart 85 arranged within said chamber and having their lower ends fixed to said casing, each contact arm being provided at its free end with a spherical concavity to closely engage a portion of one of said balls, a push pin mounted in said casing and entering said chamber for moving one of said loose balls 90 into engagement between said contact arms, said push pin being movable in an approximately horizontal direction, one loose ball being normally in engagement between said contact arms and another loose ball being normally in a position between said contact 95 arms and said push pin, the ball-engaging ends of said contact arms being disposed against the wall of said chamber and a portion of said wall which extends above said contact arms being curved forwardly with 100 respect to the axis of movement of the push pin, whereby the loose ball which is expelled from engagement between said contact arms is prevented from traveling in the same direction as the push pin moves 110 and is guided upwardly and forwardly from said contact arms so as to drop in front of the push pin, and a wire terminal electrically connected with each contact arm, substantially as described.

In testimony whereof I affix my signature in presence of two witnesses.

PAUL DRUSEIDT. [L. S.]
